UNITED STATES PATENT OFFICE.

WARREN L. BOYER, OF LONGMEADOW, MASSACHUSETTS, ASSIGNOR TO BEMIS CAR TRUCK COMPANY, OF SPRINGFIELD, MASSACHUSETTS, A CORPORATION OF DELAWARE.

RERAILER.

1,226,744.

Specification of Letters Patent.

Patented May 22, 1917.

Application filed January 26, 1917. Serial No. 144,613.

To all whom it may concern:

Be it known that I, WARREN L. BOYER, a citizen of the United States, and a resident of Longmeadow, in the county of Hampden and State of Massachusetts, have made and invented certain new and useful Improvements in Rerailers, of which the following is a specification.

My invention relates to a rerailer, and particularly to one which is adapted for replacing street railway cars, wherein the derailed wheels are located at the approximate height of the head of the rail. It is an object of my invention to provide a rerailer of the above-mentioned type which will quickly and effectively replace a car wheel upon the rail, and to so form and construct the rerailer that it may be used for replacing either the derailed wheel located between the rails or the derailed wheel which is located to the side of the rails.

A further object is to provide a rerailer which is light in weight, and accordingly may be handled with ease and despatch, and of such design that the initial pressure upon the rerailer as the wheel mounts thereon is in a downward direction, preventing the rerailer from being pushed forward.

30 A further object is to provide a rerailer in which coöperating parts are provided for engaging both the tread and flange of the derailed wheel which is located to one side of the rails, and so impart thereto a transverse thrust, so that the wheel, in moving upwardly and along the rerailer, is transversely shifted, and is moved upon the sloping throw-off nose in an oblique direction, rendering more positive the delivery of the 40 wheel to and upon the rail.

Other objects and advantages will appear as the description proceeds, wherein it is to be understood that changes in the precise embodiment of the invention may be 45 made within the scope of what is claimed without departing from the spirit thereof.

The preferred embodiment of my invention is disclosed in the accompanying drawings, wherein:

50 Figure 1 is a view in plan of a pair of my improved rerailers in the act of replacing a set of wheels upon the rails;

Fig. 2 is a view in perspective disclosing the manner in which the inside wheel is

replaced upon the rail, and Fig. 3 is a similar view disclosing the manner in which the outside wheel is replaced;

Fig. 4 is a view in vertical section taken on the line 4—4 of Fig. 3; and

Fig. 5 is a view in vertical section taken on the line 5—5 of Fig. 2.

Referring specifically to the several views, my improved rerailer is composed of the transversely and downwardly sloping delivery nose 10, the same being of the shed type form, and has the extreme outer edge 11 thereof rounded, so as to facilitate the delivery of the wheel upon the rail regardless of the angular position which the derailed wheel may have assumed with respect to the rail. Extending to the sides of the delivery nose, and connected thereto by the inclines 12, are the flat projections or ledges 13, the same merging into the inclines, and the inclines merging into the delivery nose 75 in a gradual manner, so that a wheel may pass from the flat projections to the inclines and from the inclines to the delivery nose, in a smooth manner, and without such jars and shocks as would tend to fracture 80 and break the rerailer.

The inclines 12 which connect the flat projections with the delivery nose, slope transversely as well as upwardly, and are supported along their upper and raised side 85 edges 14 by the tread-engaging arms 15, the latter preferably extending beyond the flat projections and arranged to receive the tread of the outside displaced wheel thereon. The tread-engaging arms slope upwardly to the apex 16 of the delivery nose, and in order to shift and transversely move the wheel as it is forced upwardly along the tread-engaging arms, I have provided the upstanding and obliquely-extending flanges 16', the same extending from the apex 16 of the delivery surface obliquely across the tread-engaging arms, and adapted to engage the outer edge of the wheel tread. The formation of flat projections, inclines, tread-engaging arms, and oblique flanges, extending to both sides of the delivery nose, allows the replacer to be used for replacing wheels regardless of the direction of movement of the latter.

The extreme ends of the flat projections 13 and the tread-engaging arms 15 are rounded, and in each case, terminating in a thin plate,

provide that the initial pressure upon the 5 rerailer by the wheel will be in a downward direction, anchoring the rerailer in place and preventing its being pushed forward by the wheel. Suitable webs 17 project beneath the delivery nose, inclines, and tread-engaging arms, and so internally brace the rerailer that a strong and rigid structure is provided, capable of prolonged use, without 10 danger of becoming fractured or broken in service.

In replacing the outside wheel A upon the rail, my improved rerailer is positioned as illustrated in Fig. 1, with the tread-engaging 15 gaging arm projecting beneath the wheel tread, and with the rounded delivery nose adjacent the rail head. The forward movement of the wheel causes the wheel tread to pass upwardly upon the tread-engaging 20 arm, and in so doing the flange B of the wheel comes into forcible contact with the transversely and upwardly sloping inclines 12, and the edge of the tread at the same 25 time forcibly contacts with the obliquely-extending flange 16 of the rerailer. A further movement of the wheel causes the same to be transversely shifted and delivered to the sloping throw-off nose 10 while traveling in an oblique direction, which materially 30 facilitates the further shifting of the wheel by the throw-off nose and its subsequent replacement upon the rail. In replacing the inside wheel C, my rerailer is positioned with the flat projection 13 extending beneath the wheel flange, so that the 35 forward movement of the wheel results in the flange mounting upon the flat projection and passing up the incline 12. As the wheel flange travels up the incline 12 to the sloping 40 throw-off nose 10, it is transversely shifted, which movement is accelerated as the wheel reaches the throw-off nose, from which portion it slides down to, and is replaced upon, the rail.

45 What I claim is:—

1. A rerailer consisting of a transversely sloping throw-off nose, an upwardly and transversely sloping incline connected to said throw-off nose, a plate-like projection 50 connected to said incline, and an upwardly sloping arm connected to the throw-off nose, to the upper edge of said incline, and projecting beyond the extremity of said plate-like projection.

55 2. A rerailer consisting of a transversely sloping throw-off nose, an upwardly and transversely sloping incline connected to said throw-off nose, a plate-like projection connected to said incline, and a tread-en-

gaging arm connected to the upper edge of 60 said incline and to the said throw-off nose.

3. A rerailer consisting of a transversely sloping throw-off or delivery surface, an upwardly sloping tread-engaging arm connected to said throw-off surface, and an incline 65 connected to the sloping throw-off surface and to the edge of the tread-engaging arm, and an upstanding flange extending obliquely across the tread-engaging arm.

4. A rerailer consisting of a transversely 70 sloping throw-off or delivery surface, an upwardly sloping tread-engaging arm connected to said throw-off surface, an incline 75 connected to the sloping throw-off surface and to the edge of the tread-engaging arm, an upstanding flange extending obliquely across the tread-engaging arm, and a flat plate-like projection connected to said incline.

5. A rerailer consisting of a shed-like 80 body formed with a transversely sloping throw-off surface, a tread-engaging arm terminating at the apex of the throw-off surface, an upstanding flange 85 extending obliquely across the tread-engaging arm from the apex of the said throw-off surface.

6. A rerailer consisting of a shed-like 90 body formed with a transversely sloping throw-off surface, a tread-engaging arm terminating at the apex of the throw-off surface, an upstanding flange 95 extending obliquely across the tread-engaging arm from the apex of the said throw-off surface, and a flat plate-like projection with an inclined portion connected to said tread-engaging arm and to the said sloping throw-off surface.

7. A rerailer consisting of a shed-like body having a substantially centrally located transversely sloping throw-off surface, flat plate-like projections connected to, and extending to the sides of, the said throw-off surface and merging into the same by upwardly and transversely-extending inclines, tread-engaging arms projecting beyond the 105 edges of the said flat projections and connected to the upper portions of the throw-off surface, and obliquely extending upstanding flanges projecting across the tread-engaging arms, adjacent the throw-off surface.

Signed at Springfield, in the county of 110 Hampden and State of Mass., this 17th day of January A. D. 1917.

WARREN L. BOYER.
